ELECTRIC APPLICATOR

Joseph J. Dobes, Oak Park, Ill., assignor to Cowan
Mfg. Co., Chicago, Ill., a corporation of Illinois

Application May 12, 1948, Serial No. 26,658

6 Claims. (Cl. 128—404)

1

This invention relates to an electric applicator, and more particularly to means for applying electric vibrations to the human body to relieve congestion therein.

Objects of this invention are to provide an electric applicator capable of energization from the ordinary 110 volt supply line; to provide an electric applicator of relatively simple and inexpensive construction; to provide an electric applicator capable of applying oscillations of complex form or multiple frequency and of selective intensities; to provide an electric applicator used for supplying electric vibrations to a multiplicity of congested areas of a single patient undergoing treatment or treat a multiplicity of patients at one time; to provide in an electric applicator a relatively simple but more efficient applicator pad.

Other and further objects and advantages will be apparent from the following description when taken in connection with the accompanying drawings wherein:

Fig. 1 is a view in exploded perspective of an electric applicator embodying the present invention;

Fig. 2 is an enlarged view in vertical section taken substantially along the line 2—2 of Fig. 1;

Fig. 3 is a view in vertical section taken substantially along the lines 3—3 of Fig. 2;

Fig. 4 is a view in perspective of an applicator pad forming part of the present invention;

Fig. 5 is a view in vertical section taken substantially along the line 5—5 of Fig. 4;

Fig. 6 is a schematic diagram of the circuit of the electric applicator of Figs. 1 to 5;

Fig. 7 is a perspective view of the elements that make up the applicator pad;

Fig. 8 is a fragmentary plan view of the applicator pad showing the electrical connection thereto; and

Fig. 9 is a detailed sectional view taken on the line 9—9 of Fig. 3 showing the vibrator coil construction.

As shown in the drawings, an electric applicator of the present invention may comprise a carrying case 2 provided with a handle 4 and having a back wall 6, side walls 8 and 10, a bottom wall 12 extending from the back wall 6 beyond the forward edges of the side walls 8 and 10 and terminating in an upright flange 14. The case is also provided with a shorter top wall 16 extending from the back wall 6 to the inclined front edges 18 of the upper sections of the side walls 8 and 10. Side rails 20 are secured to the inner surfaces of the side walls 8 and 10 in spaced

relation to the bottom 12 of the carrying case forming a storage compartment 22 and a support for the chassis 24 on which the various electrical instrumentalities are mounted. The chassis 24 comprises a bottom plate 26 slidably mounted on side rails 20, a vertical front panel 28 and an inclined front instrument panel 30. The chassis also comprises short side walls 32 supporting the instrument panel 30.

10 A pair of transformers 34 and 36 of the voltage step-down type and a pair of electromagnetic vibrators 38 and 40 include a relatively low frequency vibrator 42 and a relatively high frequency vibrator 44 carrying cooperating vibrator contacts 46 and 48. The vibrators 42 and 44, and hence the contacts 46 and 48 carried thereby, are connected in the usual manner in the circuit of the primary windings, not shown, of the electromagnetic vibrators 38 and 40.

20 Rheostats 50 and 52 are mounted on the inner wall of the instrument panel 30 with their adjusting shafts extending through the panel and having on their outer ends operating knobs 54, 56 cooperating with intensity indicating dials 58 and 60. Two pairs of applicator jacks 62—64, 66—68, are mounted on the instrument panel, each pair being juxtaposed to the control knob of the rheostat which controls the current supplied to the pair of jacks. Control switches 70 and 72 are mounted on the instrument panel, each controlling the connection of the unit supplying vibratory currents to the rheostat and jacks to which the switch is juxtaposed on the instrument panel. Signal indicator lamps 74 and 76 are also mounted on the instrument panel respectively in juxtaposition to the control switch, closure of which energizes the indicator lamp to indicate the energized condition of the jacks with which the lamp is associated.

30 35 40 45 The jacks 62 to 68 receive connector plugs 78 to 84 of electric applicator cords 86 to 92, each cord carrying at its outer end a terminal eyelet 94 riveted to the socket member or part 96 of a two part snap fastener, the other pin portion or part 98 of each snap fastener being secured to one of the applicator pads 100 to 106.

The applicator pads are all of the same construction and a description of the applicator pad 100 will be understood to apply also to the other applicator pads. As shown in Figs. 4 and 5, the applicator pad 100 comprises a quilted textile pad 108 of absorbent material, preferably cotton, covered on its inner surface with a textile mesh 110 such as cheese cloth, the netting 110 being covered by an electrically conductive

netting 112, preferably a copper netting, to which the pin portion or part 98 of the snap fastener is secured. The pin portion 98 of the snap fastener passes through an opening in a textile cover 114 secured to the cotton padding by binding 116 stitched to the absorbent pad 108 and the textile cover 114. It will be evident that the two parts 96 and 98 of the snap fastener serve detachably to connect the electrically conductive netting of the applicator pad to the applicator cord 86.

The applicator pads, cords and plugs attached to the cords are stored when not in use in the storage chamber 22 beneath the supporting bars 20 for the instrument chassis. The cover of the case is closed for storage or carrying purposes by a cover 118 having a front wall 120, side flanges 122 and 124 and a top portion 126, the side flanges 122 and 124 being of increasing height or depth adjacent the top portion 126 of the cover to mate with the inclined edges 18 of the side walls of the companion part of the carrying case. The cover 118 is formed at its opposite lower edges with short angle brackets 128 to interfit with the upstanding flange 14 so as to locate the cover on the other part of the carrying case, the cover being secured by the usual luggage latch, of which the part 130 is secured to the cover and companion part 132 is secured to the top 16 of the other part of the carrying case.

The circuit of the applicator is shown in Fig. 6, the supply line L-1 being connected in common by wires 134 and 136 to one terminal of each of the switches 70 and 72, the other terminals of these switches being connected to the signal indicator lamps 74 and 76 and through wires 138 and 140 to one end of each of the primary windings of the transformers 34 and 36. The other side of the lamps 74 and 76 are connected in common by wires 142 and 144 to the other supply line L-2 to which the other ends of the primary windings of the transformers 34 and 36 are also connected, by wires 146 and 148. The secondary windings of the transformers 34 and 36 are connected on one side to the wipers of the rheostats 54 and 56 and on the other side to the input terminals 150 and 152 respectively of the electromagnetic vibrators 38 and 40. Within the electromagnetic vibrators the primary windings 154 and 156 are connected to the terminals 150 and 152 and to the vibrator 42. The vibrators 44 are connected to the common input and output terminals 158 and 160. The secondary windings 162 and 164 of the vibrator are connected to the common input and output terminals 158 and 160 and to the output terminals 166 and 168. The wires 86, 88, 90 and 92 from the applicator pads are connected to the common input and output terminals 158 and 160.

In use the absorbent applicator pads are moistened or wetted, the moisture being absorbed by the absorbent, quilted pads 108. The applicator pads may be removed from their supply cords by the release of the two part snap fasteners in order to sprinkle or immerse the pads in water to moisten or wet the same. They may then be reattached to the cords and the plugs of the cords inserted in the appropriate jacks on the instrument panel. The control switch or control switches are then closed to energize the signal lamp or lamps and the transformer or transformers, the rheostat knob being set to minimum intensity position. The applicator

pads are then placed in appropriate locations with respect to the area of congestion, one pad being preferably placed in the area of the congestion, pain or muscular stiffness while the other pad is appropriately placed in spaced relation thereto along the nervous or muscular system feeding blood to the congested area, conveying the pain to the nerve centers or controlling the affected muscles. In some instances it may be desirable to use three or more pads placed in different locations or to effectively cover the circulating nervous or muscular system related to the affected area. The control knob or knobs of the rheostats are then adjusted gradually to increase the intensity to the desired value, sufficient to reach the affected area.

The relatively low frequency vibrator 42 has a predetermined, fixed relatively low natural frequency of oscillation. The relatively high frequency vibrator 44 has a fixed higher natural period of oscillation. The primary 154 or 156 is completed only when the two vibrating contacts contact one another. As the frequencies of vibration are different and are not synchronized, the contacts contact one another more or less at random, and the resulting electrical output of the transformers is of a complex form or multiple frequency. It is to be understood that in their normal condition when not oscillating that the contacts contact one another so that the primary circuit can be closed when the applicator switch is first closed. The multiple frequency resulting from applicant's vibrator is believed to have a more beneficial effect than a constantly recurring symmetrical wave shape.

Applicant has found that an electric applicator constructed in accordance with his present invention restores the normal flow of blood to congested areas thereby relieving the congestion and the pain associated with the congestion and the stiffness of muscles caused by a decrease in the normal rate of circulation of the blood through the body. Cases of arthritis which have not responded to medical treatment have yielded to application of the multi-frequency electric currents provided by the applicator of this invention.

It will be apparent from the foregoing description that applicant has provided an electric applicator capable of energization from the ordinary 110 volt supply line; an electric applicator of relatively simple and inexpensive construction; an electric applicator capable of applying vibrations of multiple frequency and of selective intensities; an electric applicator for supplying electric vibrations to a multiplicity of congested areas of a single patient undergoing treatment, or for treating a multiplicity of patients at one time, and a relatively simple but more efficient applicator pad in an electric applicator.

It will be obvious that changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. In an electric applicator, a pair of applicator pads, a plurality of electric vibrators having different frequencies of operation, means connecting said vibrator in series and to said pads, and current intensity control means in circuit with said vibrator and said applicator pads.

2. In an electric applicator, body applicator means, a transformer having a primary circuit

adapted to be connected to a source of alternating current and a secondary circuit, a series connected double frequency electric vibrator in said secondary circuit and connected to said body applicator means.

3. In an electric applicator, body applicator means, a pair of non-synchronous electric vibrators each having an input circuit and an output circuit, each of the vibrators including a plurality of series connected vibrating contacts of different natural frequencies, the input circuit being adapted to be connected to a source of alternating current, a pair of rheostats in the output circuits and means connecting said body applicator means in said output circuits. 10

4. In an electric applicator, body applicator means, a carrying case having upper and lower chambers, one of said chambers being a storage chamber for receiving said body applicator means, a multi-frequency electric vibrator supply unit mounted in the other of said chambers and having connector means for connection to the body applicator means, each of the multi-frequency electric vibrator supply units including a pair of series connected vibrating contacts having different natural frequencies. 20

5. In an electric applicator, a pair of body applicator electrodes, a plurality of electric vibrators having different frequencies of operation, and

means connecting said vibrators in series with one another and with said body applicator electrodes.

6. In an electric applicator, body applicator electrode means, an electric vibrator having a primary, a secondary, and a pair of vibrating contacts, the vibrating contacts having different natural frequencies of vibration, means connecting said secondary to said body applicator electrode means, and means connecting said primary and said pair of vibrating contacts in series, said last named means being adapted for cooperation with a source of electrical supply for energizing said primary. 15
